UNITED STATES PATENT OFFICE.

LEE DE FOREST, OF SAN FRANCISCO, CALIFORNIA, ASSIGNOR TO RADIO TELEPHONE & TELEGRAPH COMPANY, A CORPORATION OF DELAWARE.

WIRELESS-TELEGRAPH SIGNALING SYSTEM.

1,221,033.

Specification of Letters Patent.

Patented Apr. 3, 1917.

Application filed December 6, 1911. Serial No. 664,135.

To all whom it may concern:

Be it known that I, LEE DE FOREST, a citizen of the United States, residing in the city and county of San Francisco, State of California, have made a certain new and useful Invention in Wireless-Telegraph Signaling Systems, of which the following is a specification.

The object of my invention is to increase the output of wireless transmitting stations so that one station equipped with but one antenna system, and a single source of radiant energy, may perform the work of two or more transmitters, as by duplexing, triplexing, etc., and to simultaneously receive at a distant receiving station or stations, two or more messages from such transmitter.

Further objects, purposes and applications of my invention will be hereinafter more fully explained and claimed.

The invention consists substantially in the construction, combination, location and arrangement, all as will be more fully herein-after set forth, as shown in the accompanying drawing, and finally pointed out in the claims.

My invention will be described with reference to the drawing, accompanying and forming a part of this specification and in which—

Figures 1 and 2 represent diagrammatically two arrangements of transmitter circuits and Fig. 3 an arrangement of receiving circuits, whereby my invention may be carried into effect.

In the drawing, A is an antenna system; L a helix or inductance in series with the antenna and earth connection E; D, D' is a source of power. In Fig. 1, is shown at D a direct current source of potential suitable for energizing the oscillating arc K. In Fig. 2, D' is the secondary winding of a high tension transformer; H, H, are impedance coils, S is an interrupter or commutator, carrying on its periphery alternate, conducting and non-conducting segments. K₁, K₂, are transmitting keys of the Morse type; p, p₁, p₂, are points of contact on the inductance or helix L; b¹, b², are brush contacts for alternately making contact with the commutator or interrupter disk segments. G, in Fig. 2 is a spark gap, preferably of the quenched spark type; C is a condenser in the oscillating circuit containing

the gap G. In Fig. 3, L₁, L₂, are separate inductances, preferably variable; L₃, L₄, are primary coils of receiving circuit transformers; C₃, C₄, are capacities connected in shunt around L₃, L and L₄, respectively; C₁, and C₂, are variable condensers connected to the terminals of the secondary coils L₅ and L₆ of the two receiving transformers; D₁ and D₂, are leads to suitable detectors and indicating apparatus and as are commonly used in wireless telegraphy and telephony.

It is known that if during the receipt of an audible telegraph signal the transmitted current is interrupted a great number of times per second the signals may still be read as certainly as though the current were continuous. It is feasible therefore to rapidly interrupt a train of radiated energy having a certain wave length and to momentarily substitute therefor another train having another wave length, and if at the receiving station or stations, suitable circuits are prepared, attuned respectively to each radiated frequency, then two or more messages may be simultaneously transmitted and received. It is only necessary that the interruptions and restorations of each wave train be at a sufficiently high rate not to seriously interfere with the apparent continuity of each separate set of signals; and further that the several wave-lengths employed for the several messages be sufficiently divergent to enable the individual receiving circuits employed to pick up each its appropriate wave-train, to the exclusion of all the others.

Thus I have found that a frequency of signal interruption of 100 per second is sufficient to enable a skilled operator to read the signals which are received by his instrument, practically as well as if his wave train or a succession of wave impulses, were the only one employed. Moreover, a difference of five per cent. between the several wave lengths employed is ample to insure that each receiving apparatus will respond only to the signals intended for it.

In Fig. 1, I have shown a convenient method for applying my invention to the arc type of transmitter. Here the antenna inductance L, is tapped at three points, p, p₁, and p₂. If the contact p₁, is at, say the 10th turn of the helix (counting from the top or antenna contact) contact p at the 12th turn; and contact p₂ at the bottom or

13th turn, then it is obvious that when brush b_1 , is on an insulating segment of the interrupter S and while brush b_2 , is on a conducting segment, there are only 10 turns of the 5 helix in circuit when key k_1 , is closed; and 12 turns when key k_1 , is depressed or open. Similarly when the interrupter disk which is motor-driven, has advanced by the space of one tooth key k_1 is short circuited; and 10 if key k_2 is closed there are again 10 turns of the helix in circuit, but when k_2 is depressed or open, there are 13 turns in the circuit. Hence when the operators at keys 15 k_1 and k_2 are resting, as between signals of the Morse code, the transmitter radiates a wave train whose wave length is determined by the constants of its antenna system including 10 turns of the helix l . But each operator as he presses his key will cause 20 waves of different wave lengths to be radiated, one wave length being that determined by 12 turns of the helix, the other wave length being that determined by 13 turns. In no way, however, is it attempted or possible in the invention here described to radiate energy defined by more than one wave 25 length at the same instant.

In Fig. 2 the same principle is shown applied to a spark instead of an arc type of 30 transmitter. In the figure the Morse keys are shown as of the make instead of the break contact type.

By this arrangement when both keys are 35 open there is radiated a wave whose periodicity is determined by the entire helix. When brush b_1 is on an insulating segment of the disk S, the circuit of key k_1 is held open and if during that period key k_2 is closed a wave shortened by the cutting out 40 of circuit of the turns of the helix between p and p_2 is radiated. Similarly when brush b_2 is on an insulating segment the circuit of key k_2 is held open, and the length of the radiated wave is at that instant determined 45 by the key k_1 , provided that key chances to be closed at that instant.

Inasmuch as in the spark circuit shown in Fig. 2 we have two oscillating circuits, the constant circuit G, C, L and the antenna 50 circuit A L E, which latter may have any of three natural periodicities, it is advisable that these two circuits be rather closely coupled, so that the antenna system will take a sufficient amount of energy from the oscil-

lating circuit at whatever frequency the former may be attuned to. 55

In every case, to avoid excessive potentials and destructive sparking at key and interrupter contacts, it is advisable to take the taps off from the lowermost turns of the 60 helix, near the earth connection.

Keys and brush contacts may be immersed in oil, or other means taken to prevent 65 sparking, but if the potentials employed at the source are low, which is especially the case with the arc transmitter, such precautions are unnecessary.

The methods of receiving two or more wireless messages at the same station and even when using a common antenna are now 70 so well understood by those skilled in the art as to require here no especial directions. The circuital arrangements illustrated in Fig. 3 I have found admirably adapted to 75 the purpose in mind.

It is obvious that the methods hereinabove described for transmitting and receiving two sets of messages simultaneously may be extended to three or more, without departing from the scope of my invention. 80

It will be understood that many modifications may be made both in the apparatus and in the circuit arrangements herein described, and therefore I do not desire to be limited to the exact apparatus and systems 85 which I have illustrated for the purpose of more fully disclosing my invention.

I claim:

1. In a system for multiplex wireless signaling, a radiating antenna system, key controlled circuits associated therewith, keys for controlling said circuits and means for automatically shunting said keys in succession. 90

2. In a system for multi-plex wireless signaling, a radiating antenna system, key controlled circuits associated therewith, keys for controlling said circuits, and means for automatically rendering each key operative in succession. 95

In testimony whereof I have hereunto set my hand in the presence of the subscribing witnesses, on this 29th day of November A. D., 1911.

LEE DE FOREST.
